RIDDLING DEVICE

Le Roy S. Wilson, Port Huron, Mich., assignor to
 Roller Riddle Corp., Port Huron, Mich., a corporation of Michigan

Application January 30, 1947, Serial No. 725,346

1 Claim. (Cl. 209—236)

1

This invention relates to riddling devices and more particularly to an improved power driven riddling device.

It is an object of the invention to provide an improved riddling device which is simple in construction, economical of manufacture and assembly, and reliable and efficient in operation.

It is also an object of the invention to provide a riddling device having an improved construction affording a materially increased output of the device.

A further object of the invention is to provide a riddling device having improved riddle supporting means effective to prevent accumulation of the sand or other material being sifted on the peripheral portions of the riddle.

Another object of the invention is to provide, in a riddling device having a reciprocating riddle, an improved riddle supporting means operable during reciprocation of the riddle to cause the sand or other material being sifted to move toward the center of the riddle.

Other and more detailed objects will be apparent from a consideration of the following description, the accompanying drawings, and the appended claim.

For a better understanding of the invention, reference may be had to the drawings, throughout the several views of which like reference characters designate like parts and wherein:

Figure 1 is a broken elevational view of a riddling device constructed according to my invention;

Figure 2 is a plan view of the structure illustrated in Figure 1;

Figure 3 is a broken elevational view of a portion of the structure illustrated in Figure 2 taken from the line 3—3 thereof;

Figure 4 is a sectional view of the structure illustrated in Figure 3 taken substantially along the line 4—4 thereof;

Figure 5 is a sectional view of the structure illustrated in Figure 1 taken along the line 5—5 thereof;

Figure 6 is a sectional view of the structure illustrated in Figure 2 taken substantially along the line 6—6 thereof;

Figures 7, 8 and 9 are sectional views of the structure illustrated in Figure 6 taken respectively along the lines 7—7, 8—8 and 9—9;

Figure 10 is a sectional view of the structure illustrated in Figure 4 taken along the line 10—10 thereof; and

Figure 11 is a broken sectional view of the structure illustrated in Figure 8 taken substantially along the line 11—11 thereof.

2

Referring to Figures 1—4 and 10 of the drawings, the riddling device comprises a pedestal 20 having a lower casting or base 22 which supports an upright tubular column 24 which telescopically receives the lower end of a cooperating upper column 26, the upper end of which carries an upper pedestal casting 28. The upper end of the lower column 24 is longitudinally slotted and a clamping band 30 is provided which encircles the slotted end of the tubular column for releasably gripping and holding the upper column 26 at any desired elevation. The upper pedestal casting 28 has a centrally disposed downwardly extending tubular boss adapted to fit over the upper end of the column 26 and is secured thereto by set screws 32.

The upper pedestal casting 28 is also provided with opposed arms 34 extending horizontally outwardly from its central supporting boss and each carrying a horizontally disposed transversely extending pin 36 adjacent to its outer end. The pins 36 are disposed in parallel relation, extend outwardly of the opposite sides of the arms 34, and are secured in place therein and held against rotation by set screws 38 mounted in the arms 34 and engaging cooperating flats 40 provided on the pins 36. The upper casting 28 is provided with pairs of spaced ribs 42 for strengthening and supporting each of the arms 34.

An elongated channel or carriage 44, of generally C-shaped cross section, is mounted on the upwardly extending ends of the pins 36 by means of conventional caged ball bearings 46 (see Figure 10). The C-shaped carriage 44 is disposed with the open side thereof presenting downwardly, and the edges 48 thereof are turned inwardly so that the carriage 44 may engage the ball bearing cage at either the top or the bottom as required by the disposition and loading of the carriage. It will be appreciated that this construction permits movement of the carriage 44 along its own longitudinal axis but prohibits any other movement thereof, such, for example, as tilting thereof upon loading of its outer end.

Fixed to the carriage 44 are a motor 50, secured thereto by means of a bracket 52, a transmission 54 which is operatively coupled to the motor 50, and a lower riddle supporting frame 56 which is horizontally disposed and bolted or otherwise secured to the under surface of a horizontally disposed outwardly extending flange 58 integrally formed on one end of the carriage 44.

The motor is illustrated as being a conventional electric motor although it will be appreciated

that it may be a pneumatic motor or of any other suitable type. The motor is connected to the transmission 54 through a conventional flexible coupling 60 and, through the transmission 54, reciprocates an upper riddle supporting frame 62 which is supported on the lower frame 56 in a manner hereinafter described. The riddle supporting frames 56 and 62 are fabricated of angle iron and are disposed so that in the lower frame 56 the vertical flange of the angle iron extends downwardly from the horizontal flange thereof and in the upper frame 62 the vertical flange extends upwardly from the horizontal flange.

The upper frame 62 is supported on the lower frame 56 by means of a plurality of flexible links 64 and 66 which are generally vertically disposed. The links 64 are substantially longer than the links 66 and are connected externally to the frames 62 and 56 at opposite sides thereof and adjacent the ends thereof which are connected respectively to the carriage 44 and the reciprocating or driving means, or, as viewed in Figure 1, adjacent to the left hand end of the frames 56 and 62. The shorter links 66 are similarly connected to the frames 56 and 62 at opposite sides thereof and adjacent to the opposite or, as viewed in Figure 1, the right hand ends thereof. The links 64 and 66 are preferably formed of rubber and are proportioned to support the frame 62 in spaced relation above the frame 56. The opposite ends of the links 64 and 66 are connected to the frames 56 and 62 by means of brackets 68 which are riveted to the vertical flanges of the frames and which are provided with an appropriately presenting recess adapted to receive the ends of the links 64 or 66. Each end of each link 64 and 66 is securely held in its associated bracket 68 by means of a rivet 70, as is most clearly illustrated in Figure 5. The links 64 and 66 are formed of flat strips which are disposed as illustrated to permit oscillation of the upper frame 62 relative to the lower frame in the direction of the longitudinal axis of the carriage 44 but to minimize vibration of the frame 62 transversely thereof. The brackets 68 mounted on the lower frame are disposed in offset relation as may be seen in Figure 1, to connect the lower ends of the longer links 64 to the frame 56 at points below those at which the shorter links 66 are connected. Also, in the illustrated construction, the horizontal spacing of the brackets 68 mounted on the frame 56 is slightly greater than that of the brackets mounted on the frame 62.

The above described construction may be varied by swinging the movable frame 62 below the frame 56 by similar link connecting means, rather than supporting it above frame 56 as described.

Referring to Figures 1, 2 and 5, the upper frame 62 carries a sieve or riddle comprising a rectangular frame 76 one end of which is covered by a corrugated screen 78, having its peripheral portions folded upwardly along the sides of the frame 76. A short rectangular base 80 telescopically receives the screened end of the rectangular frame 76 and is fixed thereto by the rivets 82. This construction clamps the peripheral portions of the screen 78 between the frame 76 and the base 80 and, by permitting the base 80 to extend beyond the end of the frame 76, reduces the likelihood of damage to the screen. The riddle is so disposed that the corrugations of the screen 78 extend transversely of the line of

movement of the frame 62 during reciprocation thereof.

Referring to Figures 6-9 inclusive, the above-mentioned transmission 54, through which the motor 50 reciprocates the upper riddle supporting frame 62, includes a casing 90 and a cover plate 92 secured thereon by a plurality of bolts 94. An input shaft 96 is journaled in the casing 90 and operatively connected to the flexible coupling 60 through which it is driven by the motor 50. Within the casing 90, the input shaft 96 carries a bevel gear 98 secured thereto by means of a key 100 and a set screw 102. A crankshaft 104 is journaled in the casing 90 and the cover plate 92 and is disposed at right angles to the input shaft 96. The crankshaft 104 is driven through the engagement of the bevel gear 98 with a cooperating bevel gear 106 carried on the crankshaft 104 and connected thereto by a key 108. The crankshaft 104 has an eccentric portion or crank 110 which is journaled in one end of a connecting rod 112. The other end of the connecting rod 112 is bifurcated and is connected by means of a pin 114 to the lower end of an inner rocker arm 116. The upper end of the rocker arm 116 is keyed to a transmission output shaft 118, as at 120, and is secured against relative movement axially thereof by a set screw 122. The output shaft 118 is journaled in the casing 90 and the cover plate 94 and one end thereof extends outwardly of the casing 90 and carries an outer rocker arm 124 keyed thereto as at 126.

Referring to Figures 8 and 11, the outer rocker arm 124 is connected, by means of a bolt 128 extending through a conventional rubber torque bushing 130 mounted in the rocker arm, to corresponding ends of a pair of links 132. In accordance with a conventional construction of such bushings, the inner sleeve thereof extends outwardly of the rocker arm in which the bushing is employed and to which the outer sleeve is secured. The inner sleeve is clamped to the bolt 128 for rotation therewith by tightening a nut 134 on the bolt and clamping the links 132 against the ends of the inner sleeve. As best illustrated in Figure 2, the other ends of the links 132 are connected to the upper riddle supporting frame 62 by means of a bracket 136 riveted to the frame 62 and carrying a torque bushing 138 similar to the bushing 130. The links 132 are connected to the bracket 136 and clamped to the inner sleeve of the bushing 138 in the manner above described by means of a bolt 140 and a nut 142.

From a consideration of the above described construction of the transmission 54, it will be appreciated that rotation of the input shaft 96 will produce an oscillation of the output shaft 118 and reciprocation of the links 132 and consequently of the upper riddle supporting frame 62.

The electric motor 50 is connected by suitable wiring (not shown) to an automatic switch 150 mounted on a stop plate 152 bolted to and depending from the end of the carriage 44 remote from the riddle supporting frames, as illustrated in Figures 3 and 4. The switch is responsive to movement of the carriage 44 to and from the operating position illustrated in Figures 1 and 2 to automatically turn the motor 50 on and off respectively. Movement of the carriage 44 to the right, as viewed in Figure 1, is limited by the engagement of the stop plate 152 and a rubber bumper 154 mounted in the adjacent end of the upper pedestal casting 28.

To facilitate moving of the carriage between the on and off, or operating and retracting positions, a handle 156 is riveted or otherwise suitably secured to the outer end of the lower riddle supporting frame 56, as illustrated in Figures 1 and 2.

While only one specific embodiment of the invention has been illustrated and described in detail, it will be readily apparent to those skilled in the art that numerous modifications and changes may be made without departing from the spirit of the invention and the scope of the appended claim.

What is claimed is:

A riddling device comprising a base adapted to 15 be anchored to a floor or other suitable foundation, an elongated horizontally disposed carriage, means including rolling antifriction bearings supporting said carriage on said base for free movement relative thereto along the longitudinal axis 20 of the carriage, riddle supporting frame means secured to said carriage, a second riddle supporting frame disposed in spaced and substantially parallel relation to said frame means, resilient links supporting said second frame on said frame means, a motor mounted on said carriage, and means operatively connecting said motor to said 25 second frame for reciprocating said frame, said links including a pair of generally vertically disposed rubber strips disposed at opposite sides of the longitudinal axis of said carriage and con-

nected to said second frame adjacent one end thereof and a second pair of rubber strips also disposed generally vertically and at opposite sides of the axis of said carriage and substantially longer than said first named rubber strips and connected to said second frame adjacent the other end thereof, said longer strips being connected to said frame means substantially lower than the connection of said first named strips thereto, and all of said strips being connected to said second frame at substantially the same elevation.

LE ROY S. WILSON.
